(57) **CLAIM**

The ornamental design for a portable lifting apparatus, as shown and described.

DESCRIPTION

FIG. 1 is a front perspective view for a portable lifting apparatus showing my new design;

FIG. 2 is a rear perspective view;

FIG. 3 is a top plan view;

FIG. 4 is a right side elevation view, the left side elevation view being a mirror image of the right side elevation view; and,

FIG. 5 is a rear elevation view.

1 Claim, 5 Drawing Sheets

FIG. 1

FIG. 2

FIG. 3

FIG. 4

FIG. 5

UNITED STATES PATENT AND TRADEMARK OFFICE
CERTIFICATE OF CORRECTION

PATENT NO. : Des. 455,884 S
DATED : April 16, 2002
INVENTOR(S) : C. Ogrodnick
